UNITED STATES PATENT OFFICE

WILLIAM H. HOODLESS, OF PHILADELPHIA, PENNSYLVANIA

RAW-SUGAR CONVEYER

Application filed February 26, 1927. Serial No. 171,343.

Raw sugar reaches the refinery in bags. It comes frequently in very large quantities, on the Atlantic coast often in cargo lots on steamships. The practice prevailing at refineries is to store this sugar in bulk in large bins, removing it from the bags before storing it. From the bins it is withdrawn as needed for the processes of refining. Usually the raw sugar bins are placed above the ground floor of the refinery. The place of unloading of the bags from the ship or car is generally at quite a distance from the bins. Heretofore these bags containing the raw sugar were carried by travelling cranes or even by hand trucks to the mouth of a bin. The cord closing the mouth of the bags was cut by hand, and the bags lifted by main strength and emptied into the bin. The bags, which are customarily of a few standard sizes are all heavy, and the work of lifting them is exhausting and slow, and required many hands. Men frequently broke down when employed at this work.

By my device the bags are received by my conveyer first on a feeding apron, that is power driven but the movement of which is under the control of an operator who can stop or cause it to move independently of the movement of a main conveying apron, which is normally in continuous movement. This feeding apron furnishes means for distributing the bags singly or in convenient groupings along the main apron and is located at a convenient place in practice near the receiving end of the main apron for this purpose. The bags usually must be deposited on the feeding apron in irregular heaps, and as the conveyer will work more efficiently when the bags are distributed along the main apron fairly evenly, the value of the feeding apron is apparent. The main apron carries the bags that it receives from the feeding apron to the vicinity of the bins, and, near this point, the bags are gripped near their bottoms by movable carriers, while the bags are lying on the main apron, and are drawn over a downwardly inclined surface whereupon the bottom of bag is lifted gradually by the carriers, the sugar being emptied from each bag as its bottom is lifted, until the bag

is emptied. The empty bag can then be disengaged from the carrier. This inclined surface is furnished, in practice, by an auxiliary apron placed adjacent to the main belt. This auxiliary apron can form the bottom of an inclined chute down which the sugar will flow. The discharged sugar passes down the inclined apron. This arrangement of the inclined apron and bag carriers obviates the jarring that otherwise would happen, were the bags' weight thrown upon the bag carriers suddenly at the discharge end of the main apron. The conveyer substitutes machine work for the heavy labor of unloading and hastens the carrying and storage of raw sugar and obviates considerable crude, expensive and dangerous agencies like the long distance traveling cranes, and the labor required to be performed manually with it in use is directive, the hardest labor being occasional manual adjustment of the bags upon the main apron, which is many times easier than lifting the bags.

Fig. 1 is a plan of my device shown diagrammatically. Fig. 2 is an elevation of the intermittently moving apron. Fig. 3 is an elevation of the discharge end of the main apron, the bag emptier and the inclined auxiliary apron. Fig. 4 is a plan of the discharge end of the main apron and of the inclined auxiliary apron. Fig. 5 is an elevation of a bag carrier when its spring, 7, is not extended. Fig. 6 is an end elevation of the hook bus and the hooks of a bag holder. Fig. 7 is an elevation of the trolleys and upper part of a trolley hanger of a bag holder, the trolley track being indicated in section. Fig. 8 is an elevation of the driving mechanism for the main apron and inclined auxiliary apron. Fig. 9 is an elevation of a bag carrier with the spring, 7, extended, as by carrying a bag of sugar. Fig. 10 is an end elevation of the inclined auxiliary apron. Fig. 11 is an elevation of a turret and sprocket used in a modified form of bag emptier. Fig. 12 is an elevation in detail, of the drive for a feeding apron part of which Fig. 13 is a plan view. Fig. 14 is a plan of a turret and a sprocket wheel and adjacent parts adapted for use in a modified form of my invented device.

The endless apron, 1, carries the bags of raw sugar from a point convenient to the ship or car to a point near the bin. To distribute them on this apron I use a feeding apron, 3, upon which the bags are placed. Its discharge is upon the apron, 1. The mechanism driving the apron, 3, is under the control of an operator who regulates its driving mechanism by means, for instance, of an electric switch 96 so that, no matter how irregularly the bags are placed on the apron, 3, they can be discharged upon the apron, 1, so that they will be distributed sufficiently evenly on it to be taken care of by the automatic bag emptier. The apron, 3, is driven, in practice, by an electric motor, 25 that is under the control of the operator and can be started and stopped and its speed regulated by him. This motor drives the belt 3, through the worm, 19, and the gear wheel, 27, and is carried by the pulleys, 24, and 26. The aprons, 1, travels continuously at a regular speed and is supported at intervals as by the rollers, 2, 2. The driving pulley, 4, is conveniently placed at its discharge end and an idler, 5, can be used to keep the apron, 1, taut and the apron can be kept clean by the revolving brush, 19.

The receiving end of the inclined auxiliary apron, 30, is elevated to a height preferably only slightly below the level of the apron, 1, at its discharge end. The side guides, 32, keep the sugar discharged from the bags from going off the side of the apron, 30. In practice they are sloped inward at their lower sides which are positioned above the apron, 30, and are carried by the supports, 31. The driving mechanism for the apron, 30, in practice, is an electric motor 25 with a shaft, carrying a worm, 83, meshing with the gear, 84, driving the pulley, 4, and the main apron, 1, and also the sprocket wheel, 81; from which the chain, 86, the sprocket wheel, 85, and the pulley, 33, drive the inclined auxiliary apron, 30. The upper or receiving end of the apron, 30, is carried by the small roller, 9.

The automatic bag emptier is composed of a number of bag carriers, 10, which are joined together in an endless series of flexible connections, 15, and move along a closed circuit on the track, 12, on trolley, 11; the springs hold the devices for catching the bags well above them as they pass along on the main apron, 1; unyielding connections, that are slackened by the pull of the spring, 7, when the carrier is not drawn down by the weight of the bag or by the attendant (see Fig. 5) limit the distance the devices for catching the bags can be separated from the rest of the bag carrier (see Fig. 9.) In practice, the hanger, 71, has a chain, 90, which goes to a holder, 91, from which a series of chains, 16, long enough to allow the hooks, 13, to be pulled down and inserted in the bags as they pass along on the apron, 1, extend to the

bus, 14. The spring, 7, is also attached, in practice, to the carrier, 91, and by the chains, 53, to the bus, 14, these chains, 53, being short enough to make the spring, 7, lift the bus and hooks, 13, and slacken the chains, 55. A very satisfactory form of endless track trolleys and hanger is illustrated especially in Fig. 7 in which a yoke composed of the arms, 73, and 75 carries the pulleys, 11, 11, that run on the inner side of the flange, 72, which is carried from the flange, 74, by the web, 76, the loop, 70, serves conveniently to secure the end of the chain forming the flexible connections between the bag carriers.

I find it very advantageous to form the bus, 14 (see Figs. 5 and 6, especially) of a rigid back piece, 530, having loops, 58, for the supporting chains, 55, and 53, and a more flexible piece, formed of strong leather or other suitable substance, to which are secured the hooks, 13.

A pair of turrets, 175, (see Figs. 11 and 14) with radially projecting sprockets, 172, may replace the endless track, carrying the hangers, 170, of bag carriers between links, 171, that form flexible connections between them. When the weight is carried by the bag holders, they are each carried by two sprockets. The intermittently moving apron, 3, and the main apron, 1, can be driven by one driving mechanism by interposing a clutch, as 153. A driving pulley through this clutch, 153, with a bevel gear, 152, meshing with the bevel gear, 151, on the spindle, 150, of the pulley, 157, driving through a belt, 164, and a driven pulley, (not shown) the apron pulley, 163, that drives the apron, 3, which is carried also by the rollers, 162, 162, and 161.

The attendant by alternately starting and stopping the apron, 3, (aided occasionally by slight adjustments such as turning the bags without lifting them) distributes the bags sufficiently evenly along the continuously traveling apron, 1. When near the discharge end of the apron, 1, another attendant attaches the hooks, 13, 13, into the bottom of the bags (which can lie on the apron, 1 either bottom or mouth forward or sidewise) and the cords closing the mouths of the bags are cut. The forward movement of the bag causes the bag carriers to travel in their circuit continuously bringing disengaged bag carriers into position to be hooked to bags. As the bag passes off the discharge end of the apron, 1, onto the inclined auxiliary apron, 30, the hooks, 13, gradually lift the bottom of the bag allowing the sugar to flow down to the lower, the discharge end of the apron, 30, and off it, if desired, directly into a port of the receiving bin. When the bag empties, the spring, 7, has lifted, usually, the empty bag, and it can be removed readily by an attendant.

The feeding apron can be dispensed with when the bags are distributable fairly even-

ly in the main apron without its use, and other changes may be made without departing from my invention.

I claim:

- 5 1. In a machine for binning raw sugar from bags, having a constantly moving bag conveying apron and means for distributing the bags along the same, a bag emptier consisting of a series of bag carriers adapted 10 to be engaged with the bags while lying on said apron, supports for said carriers, connections between the bag carriers spacing them from each other and transmitting the motion imparted to one of said bag carriers 15 to the others, said bag carriers being movable in the direction of the movement of the bag conveying apron by the movement of the bag on the conveying apron, and an inclined apron receiving the bags from the discharge 20 end of the bag conveying apron.

2. The device as described in claim 1 wherein in said bag carriers and supports form a mutually connected endless series.

3. The device as defined in claim 1 with the 25 following additional elements, namely:—said bag carriers having supports provided with trolley wheels and stationary endless track on which said trolley wheels run.

4. In a machine for binning raw sugar 30 from bags having a constantly moving bag conveying apron, and means for distributing the bag along the same, a bag emptier comprising a series of bag carriers adapted to be engaged with the bags on the conveying 35 apron, and supports for the bag holders comprising an endless track and an endless series of hangers for carrying the bag carriers provided with flexible connections connecting said hangers, and positioned so that the path 40 of the hangers extends beyond the discharge end of the conveying apron.

5. The device as defined in claim 4 wherein the said supports are provided with yielding devices extended by the full bags of sugar, 45 but lifting the bags upwards when the bags are emptied.

6. The device as defined in claim 4 with the following additional elements:—and pulleys at the curved portions of the path of the bag 50 carriers engaging with said flexible connections.

7. In a machine for binning raw sugar from bags, the combination with a continuously moving main carrying apron, and an 55 inclined auxiliary apron, at the delivery end of the said carrying apron, of positive means for driving said aprons, a bag emptier, containing a series of mutually connected bag carriers, which carriers have means for engagement with the bottoms of the bags and a plurality of which are positioned above the delivery end of the said carrying apron, and are driven by the movement of the bags deposited on the carrying apron.

55 8. In a machine for binning raw sugar

from bags, the combination of a constantly moving bag conveying main apron, means for distributing the bags upon this apron, a bag emptier comprising a series of bag carriers adjusted to be engaged with the bottoms of the bags while the same are lying on said main apron, supports for said carriers and an inclined chute upon which the bags pass when discharged from the said main apron, the said supports for said carriers being short 70 enough to lift the said carriers and the bottoms of said bags as the bags pass from the main apron and along the chute. 75

9 9. The device as defined in claim 8, wherein the means for distributing the bags upon the main apron consists of a feed apron driven by power and under the control of the operator. 80

10 10. The device as defined in claim 8, wherein in the inclined chute upon which the bags 85 pass when discharged from the main chute has a bottom formed of a travelling apron.

11 11. In a machine for binning raw sugar wherein the bags are carried towards the bin by a main conveying apron, a bag emptier 90 comprising in combination a series of bag carriers adapted to be engaged with the bottoms of the bags, supports for said carriers comprising an element of positive length and a spring elevating the carriers above the level 95 they would reach down to if depending solely from said element of positive length.

12 12. The device as defined in claim 11, wherein the series of bag carriers are linked 100 together.

13 13. The device as defined in claim 11, wherein the series of bag carriers are moved by the movement of the bags upon the main apron when engaged with the said bags.

14 14. In a machine for binning raw sugar 105 wherein the bags are transported towards the bin by and upon a main constantly moving conveying apron, a bag emptier placed at the delivery end of said apron and comprising in combination a closed track, bag 110 carriers adapted to engage with the bottoms of said bags, and supports for said carriers placed upon said track, said supports containing springs lifting the carriers clear of the bags as carried by the main conveying 115 apron.

15 15. The device as defined in claim 14 wherein the bag carriers and supports are driven around said track by the movement of the bags with which the said carriers are engaged. 120

16 16. The device as defined in claim 14, wherein the supports for the said bag carriers are flexibly connected together and are driven around the track by the movement of the bags lying on the said main apron, with which bags the carriers are engaged. 125

17 17. The combination of a continuously travelling main conveying apron, a feed apron having its discharge at the ontake of 130

the said conveying apron, power operating mechanism for driving said feed apron under the regulation of the operator, and capable of stopping and starting the feed apron without interrupting the movement of said main conveying apron, a bag emptier situated at the discharge of the said conveying apron, and a chute for receiving the raw sugar placed at said discharge of said main conveying apron, said bag emptier comprising in combination a track, a series of bag carriers and supports for said bag carriers, the bag carriers being adapted to engage with the bags as carried by the main conveying apron and moved along said track by the said bags on said apron.

18. In a machine for binning raw sugar, the combination of a constantly moving main bag conveying apron, means for distributing the bags of sugar along the same, comprising an auxiliary apron having its discharge end over the main apron and the travel of which auxiliary apron is under the control of the operator, said machine having at its discharge end, a bag emptier, comprising movable bag carriers travelling along a fixed path and positioned to support the bags, mouth downward, after they are discharged from the discharge end of the main apron.

19. In a machine for binning raw sugar, the combination of a constantly moving main bag conveying apron, means for distributing the bags of sugar along the same under the control of the operator, said machine having at its discharge end a bag emptier comprising movable bag carriers travelling along a fixed path, a portion of said path extending beyond the discharge end of said main apron, and an inclined trough placed at the said discharge end of said main apron, the upper end of which is positioned beneath the portion of the path of the bag emptiers that extends beyond the end of the main apron.
